(57) **CLAIM**

The ornamental design for a display stand for plants, as shown and described.

DESCRIPTION

FIG. 1 is a perspective view of a display stand for plants showing my new design.

FIG. 2 is a left side elevation view thereof. The right side elevation view is a mirror image thereof.

FIG. 3 is a front elevation view thereof. The rear elevation view is identical thereto; and,

FIG. 4 is a top plan view thereof.
